UNITED STATES PATENT OFFICE.

ANDREW BARRON, OF JANESVILLE, WISCONSIN.

LIME-KILN.

SPECIFICATION forming part of Letters Patent No. 227,203, dated May 4, 1880.

Application filed March 1, 1880. (Model.)

To all whom it may concern:

Be it known that I, ANDREW BARRON, of Janesville, in the county of Rock and State of Wisconsin, have invented certain new and useful Improvements in Lime-Kilns, of which the following is a specification.

I have improved what is known as the "annular" or "tower" lime-kiln, in which the fire-pot has a series of radial flues; and the objects 10 of my improvements are to provide means for obtaining a more effective draft in the use of a portable railway-furnace; to provide an annular vaulted or arch way around the flues of the fire-pot in connection with an outer flue, 15 wall, or shell inclosing said archway, with the flues in each arranged in radial coincident positions and opening into said archway, wherein and between said flues the furnace or furnaces are operated to obtain the full draft through 20 the surrounding shell-flue, according to the direction of the wind. The outer-wall or shell flues are always open, giving light and air to the archway, within which the furnace or furnaces are operated, while the fire-pot flues are 25 temporarily closed, except such as may be supplying the necessary combustion for the oven. Under this construction the furnace is operated between the inner and outer vertical walls of the kiln, giving it a position in relation to 30 the fire-pot to obtain the full effect of the flame from the furnace directly upon the stone to be calcined, yet obtaining the advantage of double non-conducting walls. In fact I use the ordinary double walls within and between which 35 to form an annular tramway, within which the fireman operates the furnace, said tramway intersecting the radial flues, and in this way afford facilities for changing the position of the furnace to suit the direction of the wind, 40 obtain the advantage of an outside tunnel draft-flue for the furnace, a covering for the outer flue ends of the fire-pot, and a direct action of the products of combustion within the oven from the furnace.

45 I attain these objects by the construction hereinafter described, and shown in the accompanying drawings, in which—

Figure 1 represents an elevation of my improved kiln; Fig. 2, a vertical section taken 50 on the line $x-x$, and Fig. 3 a horizontal section on the line $y-y$.

The kiln is of annular form, in which the inner wall, A, of the oven B is of brick, the outer wall, C, of masonry, and an intermediate filling, D, of sand or other suitable non-conducting material. It is built upon a foundation, G, of masonry, having a tunnel, H, into which the products of calcination, from the oven are discharged.

The oven B has a pot-shaped truncated bottom, a , opening into a central passage, I, which communicates with the base tunnel H, and is provided with a slide, J, for the discharge of the calcined products. The central passage, I, is pierced by the radial fire-pot flues b , which, however, only extend to the outer side of the inner brick wall, A, of the oven. These flues are made to flare inward as much as possible, so as to give a wide flame and expose the stone as much as possible to 60 the action of the fire, the contents of the oven being kept from falling into the flues by fire-brick placed within the flaring ends of the flues and built into the top and bottom of said flues, as shown in Fig. 3.

The middle non-conducting wall, D, does not extend to the foundation G, but is supported by an arch, K, Fig. 2, extending around between and built upon the inner and the outer walls, and with sufficient headway and passage-way to form an annular tramway, c , for the furnace E or furnaces in being shifted from one flue, b , to another, to suit the direction in which the wind is blowing, to allow of the operations of the fireman, and to uncover 85 the flues, so that they extend only through the fire-pot wall.

The outer wall, C, like the oven-wall, rises from the foundation and forms the annular archway L around the fire-pot flues. It is provided with draft-flues M, formed by arched openings in coincident positions with the fire-pot flues b , so that the furnace being placed in position with the flue b is thereby also placed in position opposite the outer flue, M, or between two flues, in which the outer one gives an effective draft to the furnace. These outer arched draft-openings give light and air to the annular archway, while the outer shell, within which the draft-openings are formed, 90 covers and protects the fire-pot wall.

It will be noticed that the archway is formed

around the thickest part of the fire-pot *a*, and the formation of this archway between the inner and the outer walls shortens the flame-flues and brings the furnace nearer the fire-pot opening *I*, which is an advantage of much importance in obtaining the full benefit of the heat from an outside tramway-furnace.

These draft-openings *M* are of greater area than the flues *b*, to give ingress and egress to the archway, and it is by these outer-wall flues or openings and the archway that I am enabled to use a tramway-furnace inside of the walls of a kiln, instead of around the outerside, as heretofore. One or more furnaces may be used of suitable construction and provided with tramway-wheels for travel upon the track, as may be required for use with any particular flue or flues, the flues not in use being closed by removable cast-iron doors *d*. (Shown in Fig. 3.)

The stone is dumped into the oven by means of ordinary staging and dumping apparatus, and the products of calcination being discharged within the foundation-tunnel *H* may be conveyed away by an endless chain or apron operated in any suitable manner.

I claim—

1. The inner and the outer walls of a tower lime-kiln, separated at their junction with the foundation to form an annular vaulted or arch way, *L*, within which the oven-flues *b* open,

and within which the tramway-furnace *E* is arranged to connect said furnace with said flues, substantially as and for the purpose herein set forth.

2. The outer shell or wall of a tower lime-kiln, provided with draft-flues or openings *M*, coincident with the oven-flues *b*, in combination with the tramway-furnace *E*, arranged to connect with said oven-flues opposite the outer-wall draft flues or openings and within an annular archway formed between the inner and the outer walls, substantially as and for the purposes herein set forth.

3. A tower lime-kiln in which the tramway-furnace is inclosed within an annular vaulted or arch way formed by and between the inner and the outer walls, the flues and draft-openings wherein are coincident and on opposite sides of the furnace track, said draft-openings in the outer wall being of greater area than the coincident oven-flues, and the said archway having sufficient headway and passage-way to allow of shifting the position of the furnace in relation to the oven-flues, substantially as and for the purposes herein set forth.

In testimony whereof I have hereunto set my hand.

ANDREW BARRON.
